(57) **CLAIM**

The ornamental design for a desk front light box, as shown and described.

DESCRIPTION

FIG. 1 is a facing, perspective view of a desk front light box, wherein the break lines within the desk front light box and corresponding bracket represent indeterminate length, and line shading within the break lines represent resin material in cross-section;

FIG. 2 is a front elevational view thereof;

FIG. 3 is a back elevational thereof;

FIG. 4 is a right elevational thereof;

FIG. 5 is a left elevational thereof;

FIG. 6 is a top plan view thereof; and,

FIG. 7 is a cross-sectional view of thereof taken along line 7-7 of FIG. 6.

The back of the desk front light box configured to be covered by the desk is unornamented.

The broken lines immediately adjacent the shaded areas represent the bounds of the claimed design, while all other broken lines are for environmental or illustrative purposes only; the broken lines form no part of the claimed design.
